(57) **CLAIM**

The ornamental design for a bottle, as shown and described.

DESCRIPTION

FIG. 1 is a top, front perspective view of our new bottle; FIG. 2 is a front elevational view thereof, the rear elevational view being identical except for the unclaimed threads; FIG. 3 is a left side front elevational view thereof, the rear elevational view being identical except for the unclaimed threads;

FIG. 4 is a top plan view thereof; and,

FIG. 5 is a bottom plan view thereof.

The broken lines shown in the drawings are for illustrative purposes only and form no part of the claimed design.
